assignments, to Johnson Products Co., Boston,
Mass., a corporation of Massachusetts

Application May 1, 1934, Serial No. 51,604

Term of patent 7 years

To all whom it may concern:

Be it known that I, EDWIN ESSON, a subject of
the King of Great Britain, residing at Newton,
in the county of Middlesex and Commonwealth
of Massachusetts, have invented a new, original,
and ornamental Design for a Combined Buffet
and Heat Circulator or Article of Analogous Na-
ture, of which the following is a specification, ref-
erence being had to the accompanying drawing
forming a part thereof.

The figure is a view in perspective of the article
showing my new design.

I claim:

The ornamental design for a combined buffet
and heat circulator or article of analogous nature,
substantially as shown.

EDWIN ESSON.
